HERBERT V. KOHLER, OF SHEBOYGAN, AND FRANK G. BROTZ AND HALSTEN J. THORKELSON, OF KOHLER, WISCONSIN, ASSIGNEES TO KOHLER COMPANY, OF KOHLER, WISCONSIN, A CORPORATION OF WISCONSIN

DESIGN FOR A RADIATOR SECTION

Application filed December 14, 1929. Serial No. 33,792. Term of patent 14 years.

To all whom it may concern:

Be it known that we, HERBERT V. KOHLER, FRANK G. BROTZ and HALSTEN J. THORKELSON, all citizens of the United States, the first residing at Sheboygan and the others residing at Kohler, in the county of Sheboygan and State of Wisconsin, have invented a new, original, and ornamental Design for Radiator Section, of which the following is a specification, reference being had to the accompanying drawing, forming part thereof.

In the drawings,

Fig. 1 is an elevation of a radiator section, showing our new design.

Fig. 2 is a transverse sectional view thereof on the plane of line 2—2 of Fig. 1;

Fig. 3 is a sectional view of a portion thereof on the plane of line 3—3 of Fig. 1, and

Fig. 4 is a sectional view of a portion thereof on the plane of line 4—4 of Fig. 1.

We claim:

The ornamental design for a radiator section, as shown.

HERBERT V. KOHLER.
